DESIGN FOR A WALKING STICK

Louis G. McCorkle, Margate, N. J.

Application March 25, 1935, Serial No. 56,047

Term of patent 3½ years

To all whom it may concern:

Be it known that I, Louis G. McCorkle, a citizen of the United States, residing at Margate, in the county of Atlantic and State of New Jersey, have invented a new, original, and ornamental Design for a Walking Stick, of which the following is a specification, reference being had to the accompanying drawing, forming a part thereof, in which:

Fig. 1 is a side elevation of a walking stick, showing my new design,

Fig. 2, a detail bottom plan view of the foot,

Fig. 3, a detail top plan view of the foot,

Fig. 4, a detail side elevation of the foot, on an enlarged scale, and

Fig. 5, a detail front elevation of the foot.

The dominant feature of the design is the foot of the stick.

I claim:

The ornamental design for a walking stick, as shown and described.

In witness whereof, I have hereunto set my hand and seal at Margate City, in the county of Atlantic, State of New Jersey, this 23rd day of March, 1935, A. D.

LOUIS G. McCORKLE. [L. S.]
